(57) **CLAIM**

The ornamental design for a combined display and dispenser for batteries, as shown and described.

DESCRIPTION

FIG. 1 is a front view of the combined display and dispenser for batteries showing our new design;

FIG. 2 is a top view thereof;

FIG. 3 is a bottom view thereof;

FIG. 4 is a rear view thereof;

FIG. 5 is a right side view, the left side view being a mirror image thereof;

FIG. 6 is a perspective view of FIG. 1; and,

FIG. 7 is a perspective view, wherein the combined display and dispenser for batteries is disassembled.

The batteries are shown in broken lines in FIG. 6 for illustrative purpose only and form no part of the claimed design.
